UNITED STATES PATENT OFFICE.

ELMER W. DICKERMAN, OF WESTFIELD, MASSACHUSETTS, ASSIGNOR OF
ONE-HALF TO GEORGE E. WHIPPLE, OF SAME PLACE.

SPINNING-TOP.

SPECIFICATION forming part of Letters Patent No. 387,153, dated July 31, 1888.

Application filed March 17, 1888. Serial No. 267,559. (No model.)

To all whom it may concern:

Be it known that I, ELMER W. DICKERMAN, a citizen of the United States, residing at Westfield, in the county of Hampden and 5 State of Massachusetts, have invented new and useful Improvements in Spinning-Tops, of which the following is a specification.

The object of the present invention is to so construct a spinning-top that it may be made 10 to receive and support a percussion-cap or other explosive, and to cause an explosion of said cap at the instant of its being thrown for spinning by the concussion or compression contact of one movable part of the top against 15 said explosive; and the invention consists in the construction and combination of the parts of a top, all substantially as will hereinafter more fully appear, and be set forth in the claim.

20 In the accompanying sheet of drawings a top constructed in accordance with the present invention is illustrated, and Figures 1 and 2 are respectively a side elevation and central vertical section of same.

25 The body A of the top is axially bored or chambered from its upper side, as at a, for a portion of its height, at the bottom of which chamber is preferably inserted a block, b, of hard material, as steel or iron, &c., forming 30 the cap stop or rest B. The chamber or bore a is closed by a plug or stopper, d, extending downwardly therein, but leaving a considerable space in the chamber between its inner end and the said rest-block b, within which 35 space is disposed an independent plunger-block, h, constituting the movable and exploding part of the top. Holes or passages k, more or less in number, extend radially from the said chamber a to the sides of the 40 top-body.

To operate the top described, the plug d is removed and also the independent plunger-block, the cap or explosive placed on the rest B or bottom of the bore, and on the replacing of the plunger-block and plug and the top 45 being wound, as usual, and thrown for its spinning, striking the ground or floor, the downward impact, compression, or concussion of the plunger-block against the cap causes its explosion, the holes k preventing any muffling or deadening of the sound. 50

The indurated bearing-block b (shown in Fig. 2) may, if desired, be dispensed with in some instances, as where the wood or other material from which the top-body is composed is sufficiently hard to form a durable and effective cap-rest; but the use of such block is generally to be preferred. 55

I am aware that it is not broadly new to construct tops with a rest or support for a 60 percussion-cap, and to provide a plunger for securing for the explosion of the fulminate, and such, broadly, is not claimed by me; but

What I do specifically claim, and desire to secure by Letters Patent, is— 65

A spinning-top having formed in the body thereof a vertical chamber, and the radial passages k, leading from the sides of the top thereto, and the flat block b in the bottom of the chamber to form a cap-rest, combined 70 with the block h, loosely fitting and vertically movable in said chamber, and the stop-plug d, as described and shown, for the purpose set forth.

ELMER W. DICKERMAN.
